DESIGN FOR A DISPLAY STAND

Edward E. Peterson, Marblehead, Mass., assignor
to The Forbes Lithograph Manufacturing Com-
pany, Boston, Mass., a corporation of Massa-
chusetts

Application July 12, 1938, Serial No. 78,417

Term of patent 7 years

To all whom it may concern:

Be it known that I, Edward E. Peterson, a citizen of the United States and resident of Marblehead, in the county of Essex, State of Massachusetts, have invented a new, original, and ornamental Design for a Display Stand, of which the following is a specification, reference being had to the accompanying drawing, forming part thereof.

Fig. 1 is a view in perspective of a display stand, showing my new design.

Fig. 2 is a top plan view of the display stand on a reduced scale.

I claim:

The ornamental design for a display stand, substantially as shown.

EDWARD E. PETERSON.
